[57] CLAIM

The ornamental design for a graphics display support stand, as shown and described.

DESCRIPTION

FIG. 1 is a perspective view of a graphics display support stand showing my new design;

FIG. 2 is a top plan view;

FIG. 3 is a front elevational view;

FIG. 4 is a rear elevational view;

FIG. 5 is a bottom plan view;

FIG. 6 is a left side elevational view;

FIG. 7 is a second embodiment of that shown in FIG. 1; and,

FIG. 8 is a third embodiment of that shown in FIG. 1. The broken line showing of a letter in FIG. 1 and of a support bracket in FIG. 6 are for illustrative purposes only.

FIGS. 1-5 have been shown broken away to indicate indeterminate length.

FIG. 3

FIG. 4

FIG. 5

FIG. 6

FIG. 7

FIG. 8
